UNITED STATES PATENT OFFICE.

JOHN O. ALLEY, OF DETROIT, MICHIGAN, ASSIGNOR TO THE PENINSULAR STOVE COMPANY, OF SAME PLACE.

VAPOR-BURNER FOR STOVES.

SPECIFICATION forming part of Letters Patent No. 329,251, dated October 27, 1885.

Application filed February 19, 1885. Serial No. 156,394. (No model.)

To all whom it may concern:

Be it known that I, JOHN O. ALLEY, of Detroit, in the county of Wayne and State of Michigan, have invented a new and useful 5 Improvement in Vapor-Burners for Stoves, of which the following is a specification.

My invention consists in an improvement in vapor-burners for stoves, hereinafter fully pointed out in the claims.

10 The drawing is an elevation showing the reservoir-pipe broken off, the supply-pipe, which carries the burners, one burner in full, and the pipes for two other burners, with my invention attached.

15 T represents the usual reservoir-pipe, which carries at its upper end a reservoir for the liquid fuel, elevated above the burners; and U represents a supply-pipe running from the lower end of pipe T and carrying the burners.

20 E R S represent short pipes rising from the supply-pipe U, each of which carries a burner at its upper end, the burner being shown in full on pipe E.

N represents a cap, secured to the upper end 25 of pipe E, carrying the perforated cone W and the combining-tube K.

M L represent hollow arms, which support the valve mechanism and supply a stream of fuel or vapor to the burner, f being an ordinary valve, G the needle-point spindle, and F its handle, I being a tube having a fine perforation in its upper end to permit a stream of gas to flow into the tube K, and H being the heating-cup. All the parts of this burner are, 30 well known and form no part of my invention, so that I do not deem any more detailed description thereof necessary.

In all vapor-burners a liquid fuel is vaporized by the heat of the flame, and is burned in 40 the form of vapor. As the amount of liquid vaporized depends upon the amount of heat generated by the flame, and is governed to a great extent by the degree of temperature attained by the burner, pipe E, and supply-pipe U, it follows that when a stove, especially one having more than one burner, is run hard, all these parts become quite hot, and a large 45 supply of gas is formed. In such stoves the

gas flows from the burner irregularly, causing the flame to jump or pulsate. This difficulty 50 has been partially remedied by packing the burner-tube with asbestos or other fibrous substances; but this becomes in time clogged, so as to entirely prevent the flow of gas to the burner. My invention obviates this difficulty 55 and does away with the necessity of packing the burner-pipe.

C represents a valve on the supply-pipe U, having a hand-wheel, D, to operate it, and to this valve is fastened a piece of pipe bent into 60 the form of a trap, B, on the end of which is a tight hollow ball, A. When liquid is admitted from the reservoir to the supply-pipe U to start the stove, the valve C is opened, and the liquid flows into the trap B and ball A 65 until it compresses the air in said ball to an extent due to the liquid pressure. The confined air in the ball acts like a cushion, and yields to and compensates for any irregularities in the gas-pressure, so that the flame is steady 70 and does not jump. I prefer to use the trap B because it prevents the entrance of vapor into the ball A, as would be the case if the ball were near the burners and no trap were used.

I am aware that it is old to admit hydrocarbon to a globular generating-chamber heated from an initial generator below, for the purpose of converting the fluid in the upper generator into gas before passing to the burner. I am also aware that a gasometer containing 75 80 water has been connected by a pipe with the part of a vapor-burner where the vapor reaches and is burned, the gasometer being for the purpose of receiving surplus gas from the burning-point, so that the over pressure will not 85 check the flow of the oil to the generator. I lay no claim to either of said features. My invention differs therefrom, among other things, in attaching to the fluid-supply pipe an air-chamber, into which the fluid from the supply-pipe will pass and compress the air there- 90 in so that the compressed air will form an elastic cushion to the pressure of the liquid, so as to equalize the pressure of the latter and compensate for irregularities in the gas-pressure 95 during the operation of burning the gen-

erated gas. This air-chamber is distinct from a generating-chamber, and acts only as a pressure-chamber, as the gas is generated elsewhere.

What I claim as my invention, and desire to secure by Letters Patent, is—

1. The combination, with a vapor-burner, of an air-chamber attached to the fluid-supply pipe thereof to receive liquid passing through the pipe, whereby said fluid will compress the air in said chamber to form an elastic cushion for the fluid and gas contained in said pipe, substantially as described.
2. In a vapor-burner, the combination, with the fluid-supply pipe, of the trap B, connected therewith to receive the fluid therefrom, and the hollow ball A, to receive the fluid from said trap, substantially as described.

JOHN O. ALLEY.
